UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

WINDING MACHINE.

Application filed October 1, 1924. Serial No. 740,979.

To all whom it may concern:

Be it known that I, JOHN O. MCKEAN, a citizen of the United States, and resident of Westfield, in the county of Hampden and State of Massachusetts, have invented a new and useful Improvement in Winding Machines, of which the following is a specification.

One object of my invention is to provide certain improvements in winding machines whereby floor space is saved and the number of angles for the yarn to turn may be materially reduced between the supply spool and the winding head, thereby lessening the tension on the yarn and obviating its breakage to a greater extent than heretofore; such improvements including a common supply spool arranged vertically at one end of the winding machine as distinguished from supply spools arranged horizontally upon both sides of the machine; means such as spreaders being provided for dividing the yarn strands and leading them to the opposite sides of the machine.

A further object is to provide both automatic and manually operated brakes for the supply spool, the automatic brake serving to prevent the spool from "running ahead" when the machine is in operation and the manually operated brake serving to prevent the yarn strands from sagging as the machine is being stopped.

A further object is to provide a novel bearing support for the supply spool, constructed to permit the ready placement and removal of the spool, said bearing support also carrying the automatic and manually operated brakes for the spool.

A still further object is to provide novel, manually operated means such as a belt shifting lever for gradually starting the winding, step by step, to insure easy starting and to prevent jerks on the yarn, tending to break the same, the stop for the intermediate position of the starting lever being adjustable to obtain the best results.

A still further object is to provide a "tell-tale" on the winding shaft for indicating the speed of the shaft so that when the shaft reaches a predetermined speed the starting lever may be moved from its intermediate position to its next position to bring the winding mechanism up to its full speed.

A practical embodiment of my invention is represented in the accompanying drawings, in which

Fig. 1 represents in side elevation so much of a winding machine as will give a clear understanding of my improvements applied thereto.

Fig. 2 represents a fragmentary view, showing the manually operated brake applied to the supply spool.

Fig. 3 represents a fragmentary view, showing the top bearing for the yarn supply spool.

Fig. 4 represents a fragmentary view, showing the base bearing for the yarn supply spool.

Fig. 5 represents the winding machine in top plan with the manually operated starting lever shown in full lines in the position it assumes when the machine is idle; in dotted lines the intermediate position it assumes when the machine is being started, and in dot and dash lines the position it assumes when the machine is in full running position.

Fig. 6 represents a fragmentary view, showing the bearing support for the supply spool with the parts moved to the positions they assume to permit the placement or removal of the supply spool.

Fig. 7 represents a horizontal section taken through the yarn supply spool and its bearing support at the automatic brake.

Fig. 8 represents a detail section, on an enlarged scale, taken in the plane of the line VIII—VIII of Fig. 5, illustrating the means for adjusting the position of the intermediate step in the movement of the starting lever.

Fig. 9 represents a detail front view of the tell-tale.

The winding machine frame is denoted by 1 and the winding heads on opposite sides of the machine by 2.

The drive for the winding machine includes the drive shaft 3, provided with the fast and loose pulleys 4 and 5. The driving belt 6 leads from any suitable source of power, not shown herein. The drive shaft 3 is connected to the winding shaft 7 through the usual intermediate belt and pulley connections. The winding shaft 7 is provided with a tell-tale 8 at the end of

the machine for visually indicating to the operator the rotative speed of the winding shaft.

The means which I have shown for supplying yarn to the winding machine comprises a vertically arranged supply spool 9 which is removably positioned upon the base 10 of a suitable bearing support, located at one end of the machine. This bearing support is provided with a base bearing 11 for the lower end of the supply spool shaft 12, the said shaft being provided with a spool core block 13 and bearing block 14. The base 10 of the bearing support is provided 15 with an upright comprising a lower member 15 and an upper member 16. A swinging top bearing mechanism for the supply spool comprises a fixed collar 17, adjustably secured along the member 16 by the set screw 18, and a vertically movable laterally swinging arm 19 which is provided with a top bearing 20. The upper end of the supply spool shaft 12 is provided with the core block 21 and bearing block 22, the bearing block serving 25 to receive the top bearing 20 of the swinging arm 19. The collar 17 is provided with a recess 23 for receiving the arm 19 and holding it in its operative position.

The automatic brake mechanism for preventing the supply spool from running ahead when the machine is in operation is constructed, arranged and operated as follows:—

A collar 24 is adjustably positioned by the set screw 25 on the upper member 16 of the upright, from which collar projects an arm 26 carrying a pulley 27. The brake lever comprises a collar 28 rotatably mounted on the upper member 16, from which collar 40 projects in one direction an arm 29 carrying a brake shoe 30 and in another direction an arm 31, from which leads a flexible connection 32 over the pulley 27, which flexible connection is provided with a weight 33, tending to hold the brake shoe 30 against the side of the supply spool with the required amount of friction.

The manually operated brake manipulated to prevent the yarn strands from sagging between the supply spool and the winding heads when the machine is stopping, is constructed, arranged and operated as follows:

A collar 34 is adjustably secured by a set screw 35 to the upper member 16 of the upright, which collar forms a support for a collar 36, from which projects a laterally swinging resilient arm 37, carrying a brake shoe 38 and a handle 39. This brake shoe 38 is normally held by the arm 37 a short distance above the upper end of the supply spool but when the machine is being stopped, the operator can grasp the handle 39 and depress the arm 37 to bring the brake shoe 38 into frictional contact with the upper end

of the said spool, to keep the proper tension thereon.

To remove the supply spool, the flexible connection 32 of the automatic brake mechanism may be unshipped from the pulley 27 and the lever swung around in position out of the way of the spool. The manually operated brake arm 37 may also be swung laterally out of the way of the spool. The top bearing arm 19 may then be raised and swung laterally out of the way, thus giving ample room for the removal of the supply spool, the parts remaining in this position until the placing of another supply spool when the parts may be returned to their operative positions.

The means which I have shown for dividing the yarn strands and leading them to the opposite sides of the machine is herein shown as comprising spreaders 40, projecting laterally from one end of the machine frame, which spreaders are provided with eyes 41 which not only serve to separate the yarn strands into groups as they lead off from the supply spool but also serving to separate the individual strands and lead them to their respective winding heads 2. It will be seen that because of the vertical arrangement of the supply spool these spreaders serve to lead the yarn strands to the winding heads 95 with a minimum number of turns, thereby materially reducing the tension on the yarn strands and obviating to a very great extent the liability of the strands to break.

A manually operated means is provided 100 for starting the winding gradually and thus preventing the jerks on the yarn, which means is constructed, arranged and operated as follows:

A loop 42 of a belt shifter embraces the driving belt 6, from which loop leads a belt shifter rod 43 lengthwise of the machine to the end adjacent the yarn supply spool. The lever for operating the belt shifter is denoted at 44, which lever is pivoted on a bracket 45 projecting from the end of the winding machine frame, the short arm 46 of which lever is connected to the belt shifter rod 43 and the long arm 47 of which lever extends to a position in proximity to the yarn supply spool so that a single operator may control the starting and stopping of the machine as well as apply the manually operated brake for the supply spool.

Adjustable means are provided for causing 120 the belt shifting or starting lever to be moved in successive steps so that the winding operation will be started gradually and thereby eliminate undue strain on the yarn, which means is constructed as follows:

An arm 48 projects laterally from the bracket 45, which arm is provided with an intermediate stop block 49, adjustable toward and away from the bracket 45 by an adjusting screw 50, bolts 51 passing through 130

elongated slots 52, serving to clamp the stop block 49 in its adjusted position. The top of the stop block is slightly above the top of the bracket 45, so that when the starting 5 lever is moved to start the winding operation the arm 47 of the lever will engage the stop block 49 before the driving belt 6 is shifted from the loose pulley 5, fully on to the fast pulley 4. The operator can then 10 watch the tell-tale 8 and when the winding operation has gradually come up to the predetermined speed, the arm 47 of the starting lever may be slightly raised and its movement completed along the top of the 15 block 49 to its full running position. The arm 48 is provided with uprising abutments 53, 54, for limiting the movement of the starting lever.

From the above description it will be seen 20 that I have provided certain improvements in winding machines whereby the winding of the yarn is materially facilitated and the control thereof is better regulated, and at the same time a material amount of floor 25 space is saved.

It is evident that various changes may be resorted to in the construction, form and arrangement of the several parts without departing from the spirit and scope of my 30 invention; hence, I do not intend to be limited to the particular embodiment herein shown and described, but

What I claim is:—

1. In a winding machine, a plurality of 35 winding heads, and a common vertically disposed spool containing a plurality of yarn strands adapted to be supplied to individual winding heads.

2. In a winding machine, a plurality of 40 winding heads, and a common vertically disposed spool located at one end of the machine, containing a plurality of yarn strands adapted to be supplied to individual winding heads.

45 3. In a winding machine, a plurality of winding heads located along opposite sides of the machine, a common vertically disposed spool, containing a plurality of yarn strands adapted to be supplied to individual winding heads, and means for dividing the 50 yarn strands and leading them to their respective winding heads.

4. In a winding machine, a plurality of 55 winding heads located along opposite sides of the machine, a common vertically disposed spool located at one end of the machine, containing a plurality of yarn strands adapted to be supplied to individual winding heads, and means for dividing the 60 yarn strands and leading them to their respective winding heads.

5. In a winding machine, a plurality of 65 winding heads located along opposite sides of the machine, a common vertically disposed spool located at one end of the ma-

chine, containing a plurality of yarn strands adapted to be supplied to individual winding heads, and means for dividing the yarn strands into groups, leading them to the opposite sides of the machine, separating 70 the strands and leading them to their respective winding heads.

6. In a winding machine, a plurality of winding heads located along opposite sides of the machine, a common vertically disposed 75 spool located at one end of the machine, containing a plurality of yarn strands adapted to be supplied to individual winding heads, and spreaders carried by the machine frame for dividing the yarn strands 80 into groups, separating the strands and leading them to their respective winding heads.

7. In a winding machine, a plurality of winding heads, a common vertically disposed 85 spool containing a plurality of yarn strands adapted to be supplied to individual winding heads, an automatic brake for the spool to prevent the spool from running ahead when the machine is in operation, 90 and a manually operated brake for the spool to prevent the yarn strands from sagging as the machine is being stopped.

8. In a winding machine, a plurality of 95 winding heads located along opposite sides of the machine, a common vertically disposed spool located at one end of the machine, containing a plurality of yarn strands adapted to be supplied to individual winding heads, an automatic brake for the spool 100 to prevent the spool from running ahead when the machine is in operation, and a manually operated brake for the spool to prevent the yarn strands from sagging as the machine is being stopped. 105

9. In a winding machine, a plurality of winding heads, a common vertically disposed 110 spool containing a plurality of yarn strands adapted to be supplied to individual winding heads, an automatic brake for frictionally engaging the side of the spool to prevent the spool from running ahead when the machine is in operation, and a manually operated brake arranged in position to be brought into frictional engagement 115 with one end of the spool to prevent the yarn strands from sagging as the machine is being stopped.

10. In a winding machine, a plurality of 120 winding heads located along opposite sides of the machine, a common vertically disposed spool located at one end of the machine, containing a plurality of yarn strands adapted to be supplied to individual winding heads, an automatic brake for frictionally 125 engaging the side of the spool to prevent the spool from running ahead when the machine is in operation, and a manually operated brake arranged in position to be brought into frictional engagement 130

with one end of the spool to prevent the yarn strands from sagging as the machine is being stopped.

11. In a winding machine, the winding heads, a vertically disposed yarn supply spool therefor and means for removably mounting the spool, comprising a spool shaft, a suitable base, a base bearing thereon for the lower end of the spool shaft, 10 an upright, and a vertically movable laterally swinging arm thereon provided with a top bearing for removably engaging the upper end of the shaft.

12. In a winding machine, the winding heads, a vertically disposed yarn supply spool therefor, an automatic brake for frictionally engaging the spool and a manually operated brake arranged in position to be brought into frictional engagement 15 with the spool, and means for removably mounting the spool, comprising a spool shaft, a suitable base and its upright pro-

vided with bearings for said shaft, said upright forming a support for the automatic and manually operated brakes. 25

13. In a winding machine, the winding heads, a vertically disposed yarn supply spool therefor, an automatic brake for frictionally engaging the spool and a manually operated brake arranged in position to be 30 brought into frictional engagement with the spool, and means for removably mounting the spool, comprising a spool shaft, a suitable base and its upright provided with bearings for said shaft, said upright forming a support for the automatic and manually 35 operated brakes, said brakes being movable into and out of their operative positions.

In testimony, that I claim the foregoing 40 as my invention, I have signed my name this 25th day of June, 1924.

JOHN O. McKEAN.
